UNITED STATES PATENT OFFICE.

MARTIN VAN BUREN ETHRIDGE, OF LYNN, ASSIGNOR OF ONE-HALF TO
CALEB W. HODGDON, OF BOSTON, MASSACHUSETTS.

SHOE-LASTING JACK.

SPECIFICATION forming part of Letters Patent No. 268,650, dated December 5, 1882.

Application filed December 29, 1881. (No model.)

To all whom it may concern:

Be it known that I, MARTIN VAN BUREN ETHRIDGE, of the city of Lynn, State of Massachusetts, have invented an Improvement in 5 Shoe-Jacks, of which the following is a specification.

This invention relates to the jacks wherein the shoe-last, with the insole thereto secured, and the upper are placed and held while the 10 upper is adjusted and secured to the insole; and the invention will, in connection with the accompanying drawings, be hereinafter fully described, and specifically defined in the appended claims.

15 Figure 1 is an enlarged side elevation of the jack, showing its connection with its supporting-rod, and also showing the last in position with the shoe thereon, as indicated by dotted lines. Fig. 2 is an elevation of the 20 parts shown in Fig. 1, taken as viewed from the left in said Fig. 1, but with the omission of the dotted lines that indicate the shoe. Fig. 3 is a top or plan view of the parts shown in Figs. 1 and 2, but omitting the lines showing 25 the shoe.

In said views, *k* represents the bed-plate of the jack, upon the under side of which are shown the ears *j*, which are pivotally attached to a central ear or tenon of stud *i*, a cylindrical tenon on the lower end of which is shown as seated in the axial bore of rod *h*. This method of mounting the jack forms no part of my invention. The devices arranged upon bed-plate *k* for securing the shoe in position 30 are described as follows: The usual heel-supporting standard, *s*, is preferably formed as an integral part of said bed, while the toe-support *t* is adjustably secured to said bed by a screw-bolt, *a'*, which passes through a slot in the foot of said support, as shown, whereby 35 its position may be varied as the length of the shoe requires.

Upon the upper side of bed *k* are formed the ears *n n*, in which are secured the parallel rods 40 *m m*, upon which are pivotally mounted the clamping-jaws *l l p p*, each pair of said jaws being forced against the sides of the shoe by the cam-headed bolts *b'*, on which are mounted the levers *v*, by which said bolts are actu-

ated, the cam-shaped heads *c'* acting on the 50 inclined or cam-like disks *d'*, secured to the jaws, a coiled spring being also arranged on said bolts between the jaws, as shown, and by its expansive force opening the same when they are released. The inner faces of said 55 clamping-jaws are faced with elastic rubber to insure their perfect fitting to the contour of last *u*, and also to insure a firm adhesion or holding to the leather of the shoe, and yet preventing the scarring thereof. A toe-clamp, *w*, 60 is pivoted at its lower end to the front standard, *t*, and near the extremity of its angle-arm is provided with a thumb-screw, *e'*, to engage the insole upon last *u* and secure the same in position.

For the purpose of securing the "upper" or quarters of the shoe at the requisite height relatively to the top of the insole when said quarters are being drawn up and their edges folded upon the insole for nailing thereto, I 70 have invented a clamp which is constructed and operates as follows: An arm, *x*, is pivoted at *f'* to ears formed upon bed *k*, and upon said arm are formed or secured the elastic arms *y*, which embrace standards *s*, over which the 75 shoe-quarters (shown in dotted lines *g'*) are drawn, and when arranged at the proper height relatively to the insole on last *u* said elastic arms are forced together by a clamping-bolt, *z*, or other suitable means, thereby securing 80 the quarters from displacement while their edges are being folded upon and nailed to the insole, thereby obviating the objectionable method of securing the quarters upon the last by driving a lasting-tack through them into 85 the last.

I claim as my invention—

1. In a shoe-jack, the combination of bed-plate *k*, formed with ears *n*, the parallel rods *m*, journaled therein, and the shoe-clamping 90 jaws pivotally mounted upon said rods, substantially as specified.
2. In combination with the clamping-jaws, the clamp-compressing rod *b'*, provided with a rocking arm, *v*, and the cam-shaped bolt-head *c'*, and cam *d'*, secured upon the jaw, substantially as specified.
3. In combination with a shoe-jack, a hinged

clamp, *w*, provided with an adjustable contact-point, *e'*, to engage the insole upon the last, substantially as specified.

4. In a shoe-jack, an adjustable pair of arms, *y*, and mechanism for compressing the same, in combination with the heel-standard *s*, which enters between the shoe-quarters to receive the compressive force of said arms and secure

the quarters from displacement, substantially as specified.

MARTIN VAN BUREN ETHRIDGE.
